Patented Jan. 21, 1975

234,115

CLEANING IMPLEMENT

Timothy T. Watson, 1437 Cerritos Ave.,
Long Beach, Calif. 90813

Filed May 15, 1972, Ser. No. 253,682

Term of patent 14 years

Int. Cl. D7—05

U.S. Cl. D7—179

Fig. 1.

Fig. 2.

Fig. 3.

Fig. 4.

FIG. 1 is a perspective view of a cleaning implement showing my new design, the implement being shown in an open position;

FIG. 2 is a perspective view of a cleaning implement showing my new design, the implement being shown in a closed position;

FIG. 3 is a top plan view thereof; and

FIG. 4 is a left side elevational view thereof.

I claim:

The ornamental design for a cleaning implement, substantially as shown and described.
